[57] CLAIM

The ornamental design for the fisherman's caddy, as shown and described.

DESCRIPTION

FIG. 1 is a perspective view of the fisherman's caddy with the seat lifted up;

FIG. 2 is a front plan view thereof;

FIG. 3 is a rear plan view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a cross-sectional elevational view along line 8—8 of FIG. 6, the other interior side not shown being identical, but for the existence of a drain plug.
